UNITED STATES PATENT OFFICE

WALTER E. KELLER, OF ELKHART, INDIANA, ASSIGNOR TO THE ADLAKE COMPANY, OF CHICAGO, ILLINOIS, A CORPORATION OF ILLINOIS

SASH CONSTRUCTION

Application filed September 16, 1929. Serial No. 392,771.

This invention has to do with metal window sash, and is particularly concerned with the manner in which the frame members are connected together at the corners.

5 The primary object of the invention is to provide an improved corner connection which is tight, strong, rigid and inconspicuous, and will permit the sash to be readily taken apart for glazing.

10 Other objects and advantages of the invention will be apparent to those skilled in the art upon a full understanding of the construction, arrangement and operation of the improved connection.

15 One form of the invention is presented herein for the purpose of exemplification, but it will of course be appreciated that the invention is susceptible of embodiment in other structurally modified forms coming 20 equally within the scope of the appended claims.

In the accompanying drawing:

Fig. 1 is a fragmentary front view of a sash equipped with the corner connection of 25 the invention;

Fig. 2 is a vertical section, taken through the median plane of the sash;

Fig. 3 is an enlarged horizontal section, taken on the line 3-3 of Fig. 2;

30 Fig. 4 is an enlarged vertical section, taken on the line 4-4 of Fig. 2; and

Fig. 5 is a vertical section, corresponding to Fig. 2, showing the parts in separated relation before being assembled.

35 In the sash shown in the drawing, the adjoining ends of the frame members 10 and 11 are mitered and are interiorly reinforced by correspondingly mitered lining members 12 and 13 which are soldered or otherwise securely held in place. The lining members 40 are of inwardly opening channel formation and the mitered ends thereof are set inwardly a little from the mitered ends of the frame members whereby to insure a closed joint between the latter at 44.

The frame members 10 and 11 are detachably fastened together by an L-shaped connecting member 15. One leg 16 of the connecting member consists of two laterally spaced parallel strips 17 which have inturned

abutting end flanges 18, while the other leg 19 is of inwardly opening channel formation and has an outwardly concave back 20. The leg 16 telescopes within the end of the frame member 10 and the strips 17 are soldered or otherwise securely held in place against the sides of the lining member 12. The leg 19 telescopes within the end of the frame member 11 and is removably held therein by a plurality of screws 21 which extend through 55 countersunk apertures 22 in the outer edge of the frame member into threaded apertures 23 in the arched back 20 of the leg 19.

When the screws 21 are inserted through the apertures 22 into the apertures 23 and 60 drawn up, the mitered end of the frame member 10 will be forced longitudinally against the mitered end of the frame member 11 to produce a closed joint therebetween, and the sides of the leg 19 will be wedged outwardly 65 against the sides of the lining member 13 by the flattening action of the screws upon the arched back 20 of the leg, resulting in the production of a tight, strong and rigid corner connection which may be easily taken apart 70 for reglazing by merely removing the screws 21.

In applying the present invention to a sash, two of the L-shaped connecting members 15 are used. The two connecting members are 75 preferably mounted in the ends of the top rail of the sash, with the attaching legs 19 thereof extending downwardly from the ends of the top rail in parallel relation to each other for insertion within the upper ends of the 80 stiles of the sash, which arrangement permits a pane of glass to be inserted easily into the upwardly opening three-sided frame presented by the stiles and bottom rail upon removal of the top rail, and also serves to conceal the 85 attaching screws 21 within the vertical guides in which the stiles of the sash are adapted to slide. It will be appreciated, however, that various other arrangements of the corner members might be employed. For instance, 90 the sash might be made separable at diagonally opposite corners, in which case one of the connecting members would be permanently attached to one of the rails while the other connecting member would be permanently 95 100

connected to one of the stiles, with the attaching legs 19 of the members still, however, in parallel relation to each other.

While the particular sash shown in the drawings is reinforced adjacent the corners with lining members, it will be understood that the lining members may be dispensed with provided the sash is sufficiently rigid in construction to withstand without distortion the coupling stresses applied by the connecting members.

I claim:

1. In metal frame construction, a separable connection between adjoining ends of two tubular frame members, consisting of an L-shaped connecting member, one leg of which is secured in the end of one frame member and the other leg of which is resiliently expansible and is removably positioned in the end of the other frame member.

2. In metal sash construction, a separable connection between adjoining ends of two tubular frame members, consisting of a one-piece L-shaped connecting member, one leg of which is permanently secured in the end of one frame member and the other leg of which is removably positioned in the end of the other frame member, and means for expanding the last mentioned leg of the connecting member whereby to produce a tight connection.

3. In metal sash construction, a separable connection between adjoining mitered ends of two tubular frame members, consisting of a one-piece L-shaped connecting member, one leg of which is permanently secured in the end of one frame member and the other leg of which is removably positioned in the end of the other frame member, and means for forcing the last mentioned leg of the connecting member laterally toward the outer edge of the frame member in which it is positioned whereby to draw the mitered ends of the frame members together to produce a closed joint therebetween and at the same time expand said leg whereby to produce a tight connection.

4. In metal sash construction, a separable connection between adjoining mitered ends of two tubular frame members, consisting of a one-piece L-shaped connecting member, one leg of which is secured in the end of one frame member and the other leg of which is removably positioned in the end of the other frame member and is of inwardly opening channel formation with a reentrant groove in the back thereof, and one or more screws extending through countersunk apertures in the outer edge of the frame member in which the leg of channel formation is positioned into threaded apertures in the back of such leg, whereby to draw the back of the leg toward the outer edge of the frame member and at the same time force the sides of the leg towards the sides of the frame member.

5. In metal frame construction, a separable connection between adjoining ends of two tubular frame members, consisting of an L-shaped connecting member, one leg of which is secured in the end of one frame member and the other leg of which is arched in cross section and is removably positioned in the end of the other frame member with the edges of the arched portion against the side walls of the frame member and the concave face of the arched portion against the outer wall of the frame member, and screws extending through the outer wall of said frame member into engagement with said arched portion for slightly flattening the latter to spread apart the edges thereof.

In witness whereof I have hereunto subscribed my name.

WALTER E. KELLER.
